MATTRESS

Harold R. Strauss, Chicago, Ill.

Application October 6, 1948, Serial No. 53,009

5 Claims. (Cl. 5—351)

1

This invention relates to bed mattresses and more particularly to improvements in a waterproof and therapeutic mattress such as might be used in hospitals, institutions and the like.

Oftentimes, hospital and institutional patients suffer from maladies and sicknesses which necessitate their remaining in bed for long periods of time, and/or which affect the nervous system and muscular coordination of the human body so that elimination of body waste is involuntary. In such cases the hospital bed must be made up with protective sheets and coverings, including rubber or plastic sheeting, bed pads and the like, to protect the mattress. Oftentimes, the abovementioned protective covers are forgotten or neglected, resulting in unsanitary conditions and in some cases irreparable damage to the mattress and bedding.

It is therefore the primary object of this invention to provide a mattress which will overcome all of the aforementioned objections.

An object relating thereto is to construct a mattress with a panel of waterproof material as an integral part of the fabric outer covering.

Another object is to provide a hospital mattress for use in cases which ordinarily require additional protective bedding, but which, because of its novel construction, eliminates the necessity for such coverings.

A further object is to provide a mattress having a waterproof panel of a material which is less irritating to the skin than the materials previously used for protective coverings.

Still another object is to provide a hospital mattress which will be resistant to oils, solvents, urine, body acids and the like.

Still a further object is to afford a mattress having a protective panel with relatively high heat conductivity so that body perspiration is thereby minimized.

Yet another object is to provide a hospital mattress which will reduce the overall cost of the bedding.

Yet a further object is to provide a mattress having a waterproof panel effectively and securely positioned and constructed into the mattress cover.

And still a further object is to provide a mattress for use in hospitals and the like which, through use thereof, will reduce the amount of attention that attendants and nurses must devote to their patients.

With the foregoing and other objects in view which will appear as the description proceeds, the invention consists of certain novel features

2

of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings preferred embodiments thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a perspective view of a tufted mattress constructed in accordance with my invention, and having a portion broken away to illustrate the details of construction.

Fig. 2 is a perspective view of a similar mattress, but of the type commonly known as tuftless.

Fig. 3 is a fragmentary sectional view taken on the line 3—3 in Fig. 1, and viewed in the direction indicated.

Fig. 4 is an enlarged fragmentary sectional view taken on line 4—4 of Fig. 2 and illustrating the details of construction.

In the drawings reference numeral 12 indicates generally an inner spring mattress with a fabric outer cover 14. This outer cover comprises top and bottom sheets such as 16 (the bottom sheet is not shown in the drawings), and boxing strips 18 stitched to the body sheets of the cover to form seams 20 and 22.

The novel feature of this invention resides primarily in the construction of these top and bottom sheets. Waterproof panels or inserts such as 24 are stitched into these sheets. Thus each of the top and bottom sheets 16 is made by stitching three sections together such as a lower fabric panel 26, an upper fabric panel 28 and the waterproof panel 24 to form seams 30 and 32. These seams extend transversely across the entire mattress from the longitudinal sides of seams 20 and 22 where their marginal edges are joined to boxing strips 18. It should be noted that lower panel 26 is broader than upper panel 28 for the reason

that the waterproof panel 24 must be positioned to underlay the patient's body from the knees to the shoulders.

Longitudinal fabric, reinforcement strips such as 34 are sewn under the longitudinal edges of the panel 24 to insure the securing of these panels to the boxing strips 18. The outer edges of these reinforcement strips are secured to the boxing strips 18 by the same seams 20 and 22 which secure the waterproof panels 24 thereto. The inner edges are stitched to the panel 24 as by seams 36 and 38.

The material selected for the panel 24 is also of considerable importance to this invention. In addition to being waterproof, the panel material must also possess a number of other properties. Thus, for example, the material should be resistant to oils, urine, body acids and other solvents. It should be heat resistant and to some extent heat conductive to minimize body perspiration and indirectly improve the conditions under which bedsores form. For the same reason the material should not readily crease or fold. Although a number of plastic and synthetic rubber materials possessing or approximating the above mentioned characteristics may be employed, I have found that a synthetic-rubber material formed by the polymerization of chloroprene and commonly known as neoprene is the most desirable material.

The construction of the balance of the mattress may be varied and may be substantially of the standard and usual types. Thus, although the mattress may be of almost any conventional type of construction, only two have been selected for illustration in the drawings.

In Figs. 1 and 3 a conventional inner spring structure 40 comprising a plurality of coil springs 42 positioned between tie sheets 44 and 46 is illustrated. A filler material 48, such as cotton and the like, is disposed therein between the interstices as well as between the innerspring structure 40 and the outer cover 14. Ventilators such as 50 are provided in the sides of the mattress, and carrying straps such as 52 are also provided on both sides of the mattress.

It will also be noted that the mattress shown in Fig. 1 is partially tufted with buttons such as 54 secured on the top and bottom sheets 16 of the upper and lower fabric panels 26 and 28. The waterproof panel 24 is not tufted so as to insure a continuous waterproof sheet.

In Figs. 2 and 4, a modification of the mattress construction is shown. Similar parts are designated by like numerals with an added suffix "a."

In this modification the panel 24A is affixed and positioned within the outer cover 14a in approximately the same manner as employed in the previously described embodiment. However, in this modification the mattress is of the felt filled rather than inner-spring construction, and the entire mattress is completely tuftless rather than partially tufted as in the embodiment shown in Fig. 1.

Thus it should readily be apparent that this invention affords a mattress which is waterproof in strategic parts and which entirely eliminates the necessity for specially preparing a bed with additional protective bedding. Thus, this mattress not only reduces the over-all cost of the bedding, but insures an improved sanitary condition wholly independent of the vigilance and constant attention of the hospital attendants and nurses. Moreover, by making the mattress re-

versible, the life of the mattress itself is considerably extended.

It is believed that my invention, its mode of construction and assembly, and many of its advantages should be readily understood from the foregoing without further description, and it should also be manifest that while preferred embodiments of the invention have been shown and described for illustrative purposes, the structural details are nevertheless capable of wide variation within the purview of my invention as defined in the appended claims.

What I claim and desire to secure by Letters Patent of the United States is:

15. In a mattress of the character described, an outer cover comprising top and bottom sheets, a boxing strip affixed by continuous seams to the marginal edges of said top and bottom sheets, each of said top and bottom sheets comprising a plurality of transverse panels at least one of which is made from a water-proof material.
20. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
25. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
30. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
35. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
40. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
45. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
50. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
55. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
60. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
65. In a mattress of the character described, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent transverse marginal edges of said water-proof panel.
70. In a mattress of the character described, the combination of a pair of tie sheets, a plurality of spaced coil springs positioned between said sheets, a shock absorbent filler also positioned

between said tie sheets, an outer cover comprising top and bottom sheets, a boxing strip affixed by continuous seams to the marginal edges of said top and bottom sheets, each of said top and bottom sheets comprising a panel of water-proof material having its longitudinal marginal edges affixed by seams to said boxing strip, and a pair of fabric panels with their longitudinal marginal edges aligned with the longitudinal edges of said water-proof panel and affixed by continuations of the same seams to said boxing strip, one of each of the transverse marginal edges of said fabric panels affixed by seams to the adjacent

transverse marginal edges of said water-proof panel.
